United States Patent Office.

A. L. TAYLOR, OF SPRINGFIELD, VERMONT.

Letters Patent No. 76,547, dated April 7, 1868.

IMPROVED CLOTHES-PIN.

The Schedule referred to in these Letters Patent and making part of the same.

TO ALL WHOM IT MAY CONCERN:

Be it known that I, A. L. TAYLOR, of Springfield, in the county of Windsor, and State of Vermont, have invented a new and improved Clothes-Pin; and I do hereby declare that the following is a full, clear, and exact description thereof, which will enable others skilled in the art to make and use the same, reference being had to the accompanying drawings forming part of this specification.

This invention relates to a new and useful improvement in the ordinary wooden clothes-pin, those which are provided with rigid prongs, formed by slotting a stick of suitable dimensions in a longitudinal direction.

The invention consists in providing such class or kind of clothes-pins with a catch or fastening, arranged or applied in such a manner that the pin will be effectually prevented from continually slipping off from the line and freeing the clothes therefrom—a contingency of frequent occurrence, especially in windy weather.

The accompanying drawing represents a perspective view of my invention.

A represents a clothes-pin constructed substantially on the old or original plan, *a a* representing the two prongs, and *b* the body or main portion of the pin. This being an old or well-known form of clothes-pin, does not require a special description.

In one side of this pin A there is made a rebate or recess, *c*, in which the catch or fastening B is fitted, so as to be flush with the side of the pin. This catch or fastening is made of a piece of wood having a curved inner edge, with a rounded prominence, *d*, near its centre, and a concave near its lower end, to form a hook, *e*, as clearly shown in the drawing. A wire or any suitable pivot, *f*, passes with the catch or fastening at about its centre, and works freely upon it, and a spiral spring, *g*, is interposed between the upper end of the catch or fastening and the inner side of the rebate or recess *c*, said spring having a tendency to keep the hook *e* across the slot *h*, which forms the prongs *a a* of the pin, as will be fully understood by referring to the drawing.

It will be seen from the above description that by pressing inward the upper end of the catch or fastening B, the hook *E* will be moved outward, so as to admit of the prongs *a a* being fitted over a piece of clothing or other article on the line, and when the pin is fully pressed down, the upper end of the catch or fastening is liberated, and the spring *g* will force the hook *e* under the line, and effectually secure the pin, and consequently the clothing or other article, thereto.

By this simple improvement, the difficulty attending the use of the ordinary clothes-pin, to wit, their casual detachment from the clothes-line, is effectually prevented.

I claim as new, and desire to secure by Letters Patent—

The combination of the hook or fastening B with an ordinary clothes-pin A, when the fastening is constructed and applied to the outer side of the pin, substantially as herein shown and described.

A. L. TAYLOR.
